UNITED STATES PATENT OFFICE.

JOHN J. HENDLER, OF KANSAS CITY, MISSOURI.

APPARATUS FOR GENERATING ACETYLENE GAS.

SPECIFICATION forming part of Letters Patent No. 719,665, dated February 3, 1903.

Application filed March 11, 1901. Serial No. 50,565. (No model.)

To all whom it may concern:

Be it known that I, JOHN J. HENDLER, of Kansas City, in the county of Jackson, in the State of Missouri, have invented certain new and useful Improvements in Apparatus for Generating and Burning Acetylene and other Gases, of which the following is a full, clear, and exact description, reference being had to the accompanying drawings, which form a part of this specification.

My invention relates to improvements in apparatus for generating acetylene and other gases; and my invention consists in certain features of novelty hereinafter described, and pointed out in the claims.

Figure 1 represents a vertical section of the apparatus. Fig. 2 represents an elevation of a portion of the generating-chamber, showing the lower part of the overflow-pipe.

Similar numerals refer to similar parts in both views.

1 represents a generating-chamber. 2 represents a water-reservoir surrounding the upper part of said generating-chamber. 3 represents a tube communicating with said water-reservoir at its bottom or lowest point and with said generating-chamber near the bottom thereof. 4 represents a pipe of larger area in cross-section than the tube 3, communicating with said generating-chamber near the bottom and extending into said water-reservoir nearly to the top thereof. Said pipe is preferably flattened throughout, or more particularly at its lower end, providing a narrow elongated mouth, so that the opening in the generating-chamber to receive said pipe may be confined as closely to the bottom thereof, it being desirable that the outlet to pipe 4 should be wholly below the outlet to the tube 3. Within said generating-chamber is a cell 5 for containing the calcium carbide or like material from which the gas is to be generated. Said cell is mounted upon legs 6 above the bottom of the generating-chamber and has its bottom arranged at an inclination to the bottom of said chamber, as shown, and provided with openings 5^a at or near its bottom. Within said cell are provided wick-tubes 7, communicating with the openings 5^a and provided with perforations 8, and within said tubes is provided a pack-

ing 9 of wicking or like material, such as will carry the water up said tubes and permit it to percolate through the perforations 8 into said cell. The generating-chamber is closed by a cap 10, a gasket 11 being interposed to insure against leakage. Upon said cap is mounted a valve 12, with which may be connected a burner 13, providing a convenient lamp, or a hose or tubing may be connected therewith and the gas conveyed to any desired point.

To fill the water-reservoir, an opening 14 is provided, arranged to be closed by a cap 15, having a vent-hole 16. The water-reservoir being supplied with water the water will thence pass through the tube 3 into the generating-chamber. When the water rises in said chamber to the level of the carbid-cell, a portion thereof will be carried by the wicking up the tubes 7 and will pass through the perforations 8 into said cell, and coming in contact with the material therein the decomposition will begin, accompanied by the generation of gas. The bottom of said cell being inclined, but a small portion of the body of the carbid will be at first exposed to the action of the water, and hence the generation of the gas at the beginning of the operation will be more gradual, and also by reason of the packing in the tubes 7 the passage of the water into the cell will be restrained, and as by the capillary action of the packing the water is carried up said tubes it is supplied more slowly and over a larger surface of a carbid than if admitted once to the cell without the interposition of said packing. As the gas is generated and the pressure increases the water will be forced out of the generating-chamber through the tube 3 and pipe 4 of comparatively large area. The return flow of water will be mainly through pipe 4, the water overflowing from said pipe into the reservoir. Then if the valve 12 be opened and the gas permitted to flow from the generating-chamber as the pressure in said chamber decreases the water from the reservoir will return to said chamber slowly through said tube 3, the size of said tube being such that the pressure of the water in the reservoir will not materially affect the pressure of the gas in said chamber, but will flow back through said tube at substantially the

same rate that the gas escapes under the gas-pressure in said chamber until the water rises to such height as to be again carried by the wicking into the carbid-cell.

5 It will be observed that when the pressure of the gas generated expels the water from the generating-chamber, as above noted, the packing in the tubes remaining saturated with water, the moisture therefrom will continue to permeate the carbid in the cell, so that the generation of gas will at no time wholly cease during the interval between the expulsion and return of the water, and by reason of such moisture the residuum of the carbid already 10 decomposed will not be dried by the heat generated by the decomposition and form a crust, preventing the action of the water as it returns to come in contact therewith, and excessive heating will be in great measure, if 15 not wholly, prevented. Thus a more economical and uniform generation of the gas, a more uniform pressure of the gas, and a more steady and uniform flame at the burner is maintained than when the water is permitted 20 to come directly into contact with the carbid as it flows into the generating-chamber. For convenience in handling the carbid may be placed in the cell in a sack, as shown in dotted lines, the material of the sack acting 25 also in some degree to remove the impurities from the gas.

If desired, the tube 3 may be omitted and a small opening 17 provided in the pipe 4, near the bottom of the reservoir, for the return 30 flow of the water. If an excessive gas-pressure should at any time be generated in the generating-chamber, the gas will pass off through the tube 3 and escape through the vent-hole 16 in cap 15. That such escape of 35 gas may be through tube 3, the inlet of said tube to the generating-chamber is placed further from the bottom of said chamber than the inlet of the pipe 4. If desired, a nozzle 40 18 may be provided communicating with the vent-hole 16, to which may be connected a tube or hose for conveying away the escaping gas.

Among the advantages presented by this apparatus may be mentioned, first, it is not 45 affected in its operation by any jolting or jar-ring or rolling short of complete overturning, for the reason that by such action an excessive amount of water will not be thrown upon the carbid to produce excessive and dangerous 50 generation; second, with this apparatus the lamp-carbid as it comes from the factory may be used with as good effect as the granulated or other broken form, thus saving the 55 large per cent. of waste of gas incident to 60 such preparation for use.

Having thus fully described my improve-

ments, what I claim as my invention, and desire to secure by Letters Patent, is—

1. In the apparatus of the class described, the combination of a generating-chamber provided with a controlled outlet, a carbid-cell arranged in said chamber having its lower end supported above the floor of the generating-chamber, one or more inlet-openings in the bottom of said cell, wicking extending 65 from the inlet-level of the said cell upwardly within the latter, a reservoir supported at a level above the lower inlet end of the cell, a pipe of restricted size affording communication between the bottom of the generator and 70 the bottom of the reservoir, and a second pipe of larger size forming a free communication between the lower end of the generating-chamber and the upper part of the reservoir at 75 a point above the normal liquid-level 80 therein.

2. In the apparatus of the class described, the combination of a generating-chamber provided with a controlled outlet, a carbid-cell arranged in said chamber having its lower 85 end supported above the floor of the generating-chamber, one or more inlet-openings in the bottom of said cell, wicking extending from the inlet-level of the said cell upwardly within the latter, a reservoir supported at a 90 level above the lower inlet end of the cell, a pipe of restricted size affording communication between the bottom of the generator and the bottom of the reservoir, a second pipe of 95 larger size forming a free communication between the lower end of the generating-chamber and the upper part of the reservoir at a point above the normal liquid-level therein, and a vent-aperture in the upper part of the reservoir. 100

3. In an apparatus of the class described the combination of a generating-chamber, having a valved outlet, a carbid-cell arranged in said chamber, perforated tubes in said cell provided with a packing adapted to carry the 105 water through said tubes, a water-reservoir, mounted upon said chamber, a tube communicating with said chamber near the bottom thereof and with said water-reservoir toward the top thereof, of such size as to permit the 110 water to flow freely from said chamber under pressure of the gas, and a tube communicating with said chamber near the bottom and with said water-reservoir at or near its bottom, and of such size as to form a restricted 115 return-passage for the water to said chamber as the gas-pressure is relieved, substantially as set forth.

JOHN J. HENDLER.
